ATTORNEY

UNITED STATES PATENT OFFICE.

WILLIAM S. BECHTOLD, OF NEWARK, NEW JERSEY, ASSIGNOR TO JULIUS ESCHWEGE AND MAX G. COHN, OF NEW YORK, N. Y.

DESIGN FOR A HAIR-RETAINER.

SPECIFICATION forming part of Design No. 33,726, dated December 18, 1900.

Application filed November 3, 1900. Serial No. 35,428. Term of patent 7 years.

To all whom it may concern:

Be it known that I, WILLIAM SIMON BECHTOLD, a citizen of the United States, and a resident of Newark, county of Essex, State of New Jersey, have invented and produced a new and original Design for a Hair-Retainer, of which the following is a specification, reference being had to the accompanying drawings, forming part thereof.

10 Figure 1 represents an outside elevation of a hair-retainer embodying my new design. Fig. 2 is a plan view of the same, and Fig. 3 is a central vertical elevation of the same.

The leading and material feature of my 15 new hair-retainer design consists of a narrow open frame having curvilinear sides, the upper side *a* having reverse curves or curvature of a compound character and the lower side *b* being substantially formed with a single 20 curve, as shown at the Fig. 1 representation, the whole of the open frame being longitudi-

nally curved, as represented in the plan view, Fig. 2. The ends of the frame extend inwardly—that is, they project from the concave side of the hair-retainer—to form ears *c c*, which have pin holes or perforations *d d*. A set of short teeth *e* project inwardly from the lower edge of the side *b* of the frame and upwardly at an angle to the frame, as clearly shown at Fig. 3.

Having described my new invention, what I claim as new, and desire to secure by Letters Patent, is—

The design for a hair-retainer as herein shown and described.

In testimony whereof I have hereunto subscribed my name this 2d day of November, 1900.

WM. S. BECHTOLD.
